DEVICE AND CATHODE-RAY TUBES FOR STABILISING HIGH VOLTAGES

Simon van der Meer, Eindhoven, Netherlands, assignor, by mesne assignments, to North American Philips Company, Inc., New York, N. Y., a corporation of Delaware

Application December 9, 1954, Serial No. 474,174

Claims priority, application Netherlands January 22, 1954

4 Claims. (Cl. 315—25)

This invention relates to devices comprising cathode-ray tubes for stabilising high voltages and to cathode-ray tubes for use in such devices.

In several cases it is necessary for high voltages and very high voltages to be accurately stabilised at a predetermined value for a long period, the permissible variations in voltage having to be smaller than, for example, 0.05%. Such is the case inter alia in electron-diffraction apparatus, micro-analysers, X-ray apparatus and the like. Such devices usually operate at voltages of 30 kilovolts and higher.

It is known to stabilise the voltage of an electron microscope with the use of a cathode-ray tube, of which the ray of electrons extends between two parallel pole-pieces of an electromagnet, thus traversing an angle of about 90°. The velocity of the electrons and hence the curvature of the path of electrons between the pole-pieces is dependent upon the voltage to be stabilised. If this voltage increases, the electrons are accelerated to a greater extent, resulting in a greater radius of curvature of the path between the pole-pieces. The value of the voltage to be stabilised may be maintained constant by controlling this voltage manually or automatically in such manner that the curvature of the path is maintained constant in that, for example, a luminous point produced by the ray on a fluorescent screen is maintained at a determined area. However, such a device is in many cases not sufficiently sensitive for the above-mentioned purposes.

The voltage may be readjusted automatically, for example, with the use of a device as described in Physical Review, vol. 70, pages 884—885, in which deviations of the beam from its normal position result in variations in the current distribution over a pair of collector plates. Said current variations, after being amplified, serve to control the high voltage.

A satisfactory stabilisation which affords material advantages in regard to sensitivity and structure may be obtained by providing a device for stabilising high voltages comprising a cathode-ray tube in which a ray of electrons is deflected in a constant magnetic field comprising regions of great field strength and adjoining regions of smaller field strength. The curvature of the path of electrons is dependent upon the voltage to be stabilised, which ray of electrons partly strikes a collector electrode if the voltage to be stabilized has the correct value, the variations in the current to the said electrode serving to control the voltage to be stabilized. According to the invention, at the correct value of the voltage to be stabilized, the beam extends at least through part of its path in the vicinity of, and substantially in parallel with, the transition zone between a region of great field strength and a region of smaller field strength, whereby the part of the ray of electrons striking the collector varies and the ray at the same time enters a region of smaller field strength if the voltage to be stabilised increases to an undesirable extent.

Use is preferably made of a permanent magnet having pole-pieces in the form of semi-circular discs. By pro-

2

viding opposing grooves in the adjacent surfaces of the poles, it is possible to obtain regions of different field strength, between which the field strength exhibits a high gradient, since at the grooves the spacing between the pole surfaces is greater than at the other areas. By providing different grooves which are required to extend in parallel with the last part of a corresponding path of electrons, it is possible to utilize the device for different voltages. In the simplest embodiment use is made of semi-circular disc-shaped pole-pieces, between which the ray of electrons enters tangentially and describes an arc of, say, 180° in parallel with the curved edges of the poles to strike at last the edge of a collector electrode. A high sensitivity is obtained owing to the particular arrangement according to the invention, since in the case of an unwanted increase in the voltage to be stabilized, as a result of which the velocity of the electrons in the ray and hence also the radius of the path of electrons between the pole-pieces increases, this increase in radius becomes even higher due to the ray of electrons, which is in a field strength of high gradient, moving towards the adjoining region of smaller field strength. Consequently, comparatively small deviations from the voltage to be stabilized can bring about comparatively great variations in the curvature of the path of electrons and hence in the current to the collector electrode. The variations in the current to the collector electrode, after being amplified, serve to readjust the voltage to be stabilized, in order to maintain it constant. The use of a permanent magnet permits of obtaining a magnetic field of very constant strength. Deviations resulting from variations in temperature may be either compensated by known means or avoided by the provision of temperature control devices.

In order that the invention may be readily carried into effect, it will now be described with reference to the accompanying drawings, given by way of example, in which

Figs. 1 and 2 show a determined embodiment of a tube for use in a device according to the invention.

Fig. 3 shows a curve.

Figs. 4 and 5 show details of another embodiment and

Fig. 6 shows a curve corresponding to the embodiment of Figs. 4 and 5.

In Fig. 1, reference numeral 1 indicates the bulb of a tube closed at its extremities by bases 2 and 3 respectively, in which contact pins 4 are sealed.

The tube contains an electron gun 5 which houses a cathode 6, the construction being such that the voltage to be stabilised, which is from 30 to 50 kilovolts and upwards, may be connected directly between the cathode 6 and an anode 7. The velocity of the electrons leaving the gun in the form of a thin ray is thus directly dependent upon the voltage to be stabilised. The ray of electrons extends through an aperture of anode 7 to enter tangentially between magnet poles 8 and 9. The poles 8 and 9 are secured to iron plates 10 and 11 (Fig. 2) between which a permanent magnet 12, whose polarity is indicated by letters N and S representing the north and south poles, is clamped in position. The plates 10 and 11 are connected to the anode 7 by means of a supporting plate.

The ray of electrons between the poles 8 and 9 describes a curved path which, according to the invention, extends just along the outer edges of the magnet poles where the gradient of the field strength is high, if the voltage to be stabilized has the desired value V_s . After leaving the space between the pole-pieces, the ray partly strikes the edge of a collector electrode 13 to impinge in part via the said edge upon a screen 14 which is connected to anode 7 and which prevents the glass of the bulb 1 from being struck by electrons. If the voltage V_s to be stabilized slightly increases, the radius of the path of electrons increases, which increase is enhanced due to the electrons reaching a region of smaller field strength,

viz. outside the edges of the pole-pieces. Since the edge of the collector electrode 13 is exactly opposite the edges of pole-pieces 8 and 9, a larger proportion of the ray of electrons thus extends along the said electrode.

The operation of the tube follows from Fig. 3, in which the voltage difference across a resistor R, by which the collector electrode 13 is connected to the positive terminal (earth), is plotted vertically and the voltage V_1 set up between cathode 6 and anode 7 of the electron gun is plotted horizontally.

If the voltage V_1 has a low value, the radius of the path of electrons between the pole-pieces and hence the distance X is small. Upon increasing the voltage, X steadily increases, the ray at a given moment reaching the collector electrode 13 and rendering the latter current-conveying, so that a voltage set up across R exhibits the curve shown in Fig. 3 upon increase in voltage V_1 . The width of the apex of the curve is dependent upon the width of the electrode 13, the mutual conductance of the flanks of the curve being dependent upon the diameter of the ray of electrons and the rate at which X increases with the voltage V_1 . Owing to the particular arrangement according to the invention, it is ensured that the declined flank is extremely steep due to the ray upon leaving the collector electrode at the same time entering a range of smaller field strength and the increase of X thus becoming greater. Consequently, a great variation of V_0 occurs upon small variation of V_1 in this region. This fact may be utilised by comparing the voltage V_0 with a voltage V_c and adding the difference between the said voltages, after amplification, to V_1 , thus enabling the voltage V_1 with sufficient additional amplification to be stabilised at a value V_s . Since the point P is located on a very steep portion of the curve, the value of the reference voltage V_c has little influence upon the voltage V_s . The reference voltage V_c need not therefore be constant with great accuracy. This affords the important advantage that V_c may be derived with the use of a potentiometer, from a voltage stabilised by a neon discharge tube.

In one determined embodiment, the magnet poles have a base of 2 cm. and a spacing of 0.75 mm. The field strength between the poles is 800 gauss and is produced by a permanent magnet 12. The current of the ray of electrons impinging on the electrode 13 is 15 microamps. at the utmost and $R=1$ megohm. The voltage V_0 is thus 15 volts at the utmost and about 7.5 volts at point P. The reference voltage V_c thus must also be about 7.5 volts. The voltage V_s is then stabilised at about 56 kilovolts, with an accuracy up to 0.05% for a long period, and may be constant up to about 0.005% for a short period (for example 1 minute). The voltage of 56 kilovolts may thus be maintained constant at ± 28 volts for a long period and even at ± 2.8 volts during a given measurement.

In the embodiment shown in Figs. 4 and 5, it is possible for a voltage to be stabilised at different values. The magnet poles 15, 16 in this case exhibit grooves or saw cuts 20, 21, such that adjoining regions of great and small field strength occur, between which the field strength has a high gradient, since the field strength between the opposing slots is smaller than between the other parts of the pole-pieces. The pole-pieces 15 and 16 are secured to iron plates 17, 18 between which a permanent magnet 19 is clamped in position.

The slots 20 and 21 have shapes such that the ray of electrons can extend just along the edges thereof. If the voltage of the electron gun 22 increases, the voltage set up across resistor R' exhibits the curve shown in Fig. 6, stabilisation according to the invention then being obtained at voltages V_{s1} , V_{s2} , V_{s3} . It is possible always to utilise the same reference voltage V_c , but it is alternatively possible to use a different value of V_c for each stabilised voltage V_s . The points P, P' P'' may then be provided at the centre on the strongly declined branch of

the curve. The collector electrodes 23, 24, 25 may be formed as a slotted plate. However, one edge of a plate or a slot is required to coincide with the corresponding edge of the pole-pieces or the slots therein, as viewed in the direction of the paths of the electrons.

The grooves constitute parts of half circles of different diameters and with the point of the base where the ray of electrons enters between the pole-pieces, as the common tangent point.

As a rule, strips of non-magnetic material 26, 27, respectively, for example of copper, must be clamped in the slots of the pole-pieces, in order that the paths of electrons remain spaced in the various stable positions, since otherwise the curves shown in Fig. 6 may form a continuous line to a certain extent. The slots each may have a depth of 1.5 mm. and a width of 1 mm., whilst the spacing between the pole-pieces may be 0.75 mm. as in the first-mentioned embodiment.

It will be evident that other embodiments according to the invention are possible. Thus, for example, a larger number of slots may be provided in the magnet poles and the collector electrodes may be connected to separate resistors. It is even possible for the collector electrodes to be arranged in such manner that, if the voltage to be stabilised increases, the current of the said electrodes increases, so that the points P come to lie on a strongly inclined branch of the curves shown in Figs. 3 and 6.

What is claimed is:

1. An electron tube comprising means producing a beam of electrons including means for changing the velocity of the electrons in said beam by applying a voltage thereto, means establishing a magnetic field relative to the direction of said beam to thereby cause said beam of electrons having a given velocity to follow a predetermined curved path, said magnetic field-establishing means comprising a pair of spaced pole-pieces between which the field is established, said pole-pieces having opposed curved discontinuities extending parallel to said curved path and producing adjacent regions of high and low magnetic field intensity, and a collector electrode located in said curved path to intercept at least some of said electrons in said beam and in such position that a change in the curvature of said curved path followed by the beam will be manifested by a change in the quantity of electrons intercepted by said collector, whereby a change in the voltage applied to the velocity-changing means causes the beam to be subject to the adjacent magnetic field of different intensity thereby producing a substantial change in collector current in response to a relatively minor change in applied voltage.

2. A device adapted for stabilizing high voltages comprising means producing a beam of electrons whose velocity is dependent upon the voltage to be stabilized, means producing a magnetic field in the path of said beam and substantially at right angles thereto thereby causing said beam to follow a curved path whose curvature is dependent upon the velocity of the electrons in the beam, a collector electrode located at the end of the curved path to intercept at least a part of said beam, said field-producing means comprising a pair of spaced, semi-circular pole-pieces between which the field is established and located in such manner relative to the beam that the latter enters at one end and is curved by the magnetic field to follow a path lying between the pole-pieces but adjacent the curved outer edge thereof, said collector being located at the other end of the pole-pieces and being aligned with the curved outer edge thereof, and means coupled to the collector for deriving therefrom an electrical signal dependent upon the extent of electron collection by said collector, whereby an increase in the applied high voltage to the beam-producing means causes a reduction in beam curvature and a substantial change in the extent of electron collection by the collector magnified by the beam thereupon passing from a region of

high field strength to the adjacent region of low field strength to thus further reduce the curvature of the beam.

3. A device as set forth in claim 2, in which the pole pieces have opposed curved grooves extending there- 5 along adjacent the curved path of the beam.

4. A device as set forth in claim 3, wherein a plurality of opposed grooves are present in the pole pieces, and a portion of the collector is associated and aligned with each opposed pair of said grooves.
